UNITED STATES PATENT OFFICE.

PATRICK POWERS, OF TROY, PENNSYLVANIA.

DESIGN FOR A FIRE-POT FOR FORGES.

SPECIFICATION forming part of Design No. 23,479, dated July 17, 1894.

Application filed June 22, 1894. Serial No. 515,431. Term of patent 14 years.

To all whom it may concern:

Be it known that I, PATRICK POWERS, a citizen of the United States, residing at Troy, in the county of Bradford, State of Pennsylvania, have invented and produced a new and original Design for Fire-Pots for Forges, of which the following is a specification, reference being had to the accompanying drawings, showing a part thereof.

Figure 1 is a top plan view thereof. Fig. 2 is a longitudinal vertical section on line *y* *y*. Fig. 3 is a cross section on line *x*' *x*'. Fig. 4 is a cross section on line *x* *x*. Fig. 1, these four views being deemed necessary to fully illustrate my design.

The leading feature of my design consists in a circular body increasing in size as it approaches its top and terminating in a broad

flange, the ends of said flanges being slightly concave in cross section, and the lower end 20 of the pot terminating in a slight swell or enlargement, as a unitary article.

—*A*— is the body of the pot, —*a*— are the flanges convex as shown at —*b*— and —*c*— is the swell or enlargement at the bottom. 25

What I claim, and desire to secure by Letters Patent, is—

The design for a fire pot for forges substantially as herein described and shown.

In witness whereof I have hereunto set my hand this 31st day of May, 1894.

PATRICK POWERS.

In presence of—

NICHOLAS BUCK,
JOHN COLLINS.
